SHOCK ABSORBING DOLLY BLOCK

Frank T. Sargent, Clio, Mich., assignor, by mesne assignments, to Fairmount Tool and Forging, Inc., Cleveland, Ohio, a corporation of New York

Application February 7, 1947, Serial No. 727,222

2 Claims. (Cl. 81—15)

1

My invention relates to auto-body repair tools in general and more specifically to a new and improved dolly block or hand anvil for use in removing dents and bumps from sheet metal automobile panels, such as hoods, fenders and body sections.

An object of my invention is to provide a dolly block wherein substantially all of the weight thereof is useful mass for service as a hand anvil.

Another object of my invention is to provide a dolly block capable of vibrating in working relationship to a work surface being treated.

Still another object of my invention is to provide a dolly block having the mass thereof concentrated near the working face, and having a resilient handle grip member in order that the full effect of the mass may be employed to vibrate against a work surface after being struck.

In the removing of dents and bumps from sheet metal, such as automobile panels, hoods, fenders and body sections, the principal tools used are a dinging hammer and a dolly block or hand anvil. The working surface of the wholly block is usually so constructed that different portions thereof will conform to the contour of different portions of the sheet metal structure under repair. The dolly is held against one surface of the sheet metal while hammer blows are delivered to the opposite face of the metal.

Other objects and a fuller understanding of my invention may be had by referring to the following description and claims, taken in conjunction with the accompanying drawing, in which:

Figure 1 is a top or working face view of a dolly block constructed in accordance with my invention;

Figure 2 is a side elevational view of the dolly block constructed in accordance with my invention;

Figure 3 is a front view of the dolly block of Figures 1 and 2;

Figure 4 is a cross-sectional view along the line 4—4 of Figure 3; and

Figure 5 is a cross-sectional view along the line 5—5 of Figure 3.

I believe my invention will be most readily understood if I first describe the physical construction of the dolly block illustrated in the accompanying drawing without attention to the reasons dictating such construction, and thereafter describe a method of its use whereby the purpose of its construction and the results achieved thereby will be readily understood.

Referring to the drawing, I illustrate one embodiment of my invention which is useful in re-

2

moving irregularities in automobile fenders. However, the scope of my invention is broader than the specific embodiment illustrated in the drawing, and may be adapted for use with other types and shapes of tools for similar use.

In the embodiment of my invention illustrated in the drawings, the reference character 10 refers in general to the service portion of the dolly block, and the reference character 11 refers to 10 the grip portion of the dolly block. In the general construction of tools of this type in accordance with my invention, I have concentrated the mass of the service portion of the tool in such a manner that the center of gravity of the entire 15 tool will lie as close as possible to a work face 12 of the tool, well within the body of the service portion 10. Generally, the service portion 10 may comprise steel or iron forged to suitable shapes, but may, of course, comprise any suitable material which may be devised for this purpose. The mass and weight of the service portion 10 is made of a suitable magnitude to offset the shock of dinging hammers used in conjunction therewith. However, inasmuch as a tool 20 of this nature is normally held in the hand of the operator, the weight must necessarily be small enough to be easily held in position for use without unduly tiring the operator's arm. Thus, although a large resistance inertia is desirable, the mass which may be employed to accomplish the 25 inertia is limited by the physical stamina of the operator. My invention provides for a maximum mass of material having a suitable inertia, with substantially all of the mass available to produce the inertia effect desired.

I have found that certain desirable results are accomplished by concentrating the mass in a head with the center of gravity near the anvil surface and providing a resilient handle to hold 30 the mass. This is accomplished, as illustrated in the drawing, by providing a rubber body 14 which serves as a handle and which may be suitably attached to the service portion 10. In order to more rigidly connect the service portion 10 to the rubber body handle 14, and also, in order 35 to provide more mass, I have provided for a protrusion 13 to extend from the service portion 10 into the rubber body handle 14. This protrusion 13 is illustrated by the dotted line 17 in the Figures 2 and 3. Also, the physical construction of the protrusion 13 in the specific embodiment illustrated, may be seen in cross-sectional views in the Figures 4 and 5. A shoulder 18 extends between the service portion 10 and the protrusion 40 13. The rubber body handle portion 14 is prefer-

ably bonded both to the shoulder 18 and to the protrusion 13. Any suitable bonding process may be used to bond the metal and the rubber body handle 14 together. The protrusion 13, although serving to add mass to the dolly block, affords strength to the bonding between the rubber body handle 14 and the service portion 10 by preventing transverse shearing along the shoulder 18. The protrusion 13 may be modified and reduced in any suitable manner without departing from the spirit and the scope of the present invention, provided that suitable protection against shear stress is obtained, and proper balance of the mass and center of gravity is retained.

By the provision of a service portion 10 with the work face thereon being concentrated into one large mass, and the further provision of a grip portion comprising a resilient rubber body handle 14 on the side of the service portion opposite said work face, I have produced a dolly block tool in which substantially all of the available mass is concentrated near the work face, and by the inertia effect of the mass, will sufficiently offset the shock of the dinging hammer blows.

To further accentuate the concentration of the mass near the working face 12, in the particular embodiment illustrated, I have provided for the service portion 10 to be formed with a toe portion 16. Thus, the particular embodiment illustrated comprises a heel portion 15, a toe portion 16 and a protrusion 13. The complete tool, of course, is then accomplished by adding the resilient rubber body handle 14 as described. The extended toe portion 16 provides a somewhat larger work face 12 than could otherwise be accomplished for the same mass, but also positions the center of gravity of the entire tool closer to the work face 12.

My invention comprises a distinct advantage over prior dolly blocks in the concentration of the mass near the work face 12, in conjunction with the resilient rubber grip handle portion 14. The dolly blocks usually provided are made to the maximum weight which is convenient for the operator to handle. Therefore, in the type of work wherein it is desirable to have a maximum resistance to the dinging hammer blow, the dolly block tool made in accordance with the present invention is extremely desirable. It will readily be seen, that since a maximum weight for the dolly block is conditioned upon the maximum weight which an operator can conveniently hold, the provision of a dolly block in which the mass is distributed rather than concentrated as I have done in the present invention, will have neither the desirable mass effect at the point of impact, nor the very desirable moment of inertia characteristics which may be attributed to the concentration of mass near the work face 12. It is of course understood, that although a dolly block of equal mass might well be provided in which the mass is distributed away from the work face 12, this mass would have useful effect only when the dinging hammer blow is applied directly along an axis of the tool. That is, in a dolly block in which the mass is distributed, a glancing blow as applied by the trade, would cause the block to bounce a greater distance away from the surface of the work even though the total mass were the same as provided in the present invention. Therefore, as set forth previously, the purpose of the construction as described, is to produce the desirable mass and moment of inertia effect which will eliminate excessive bounding of the dolly block tool after being struck by a dinging hammer.

The rubber body handle grip 14 serves the pur-

pose of allowing the service portion 10 to rebound several times quickly against the surface being treated after the blow by the hammer. That is, as the hammer is caused to strike the opposite face of the work from which the dolly block is in contact, the resilient grip handle 14 depresses under the blow and quickly rebounds the working face 12 of the service portion 10 against the surface being treated, thereby giving an added blow, the vibration of which hastens the metal bumping operation. By the use of my dolly, the operator is able to exert continuous tension in holding the dolly block against the surface of the metal being worked without fear of any stretching of the metal due to a dead blow being imparted to the metal. However, full resistance to the blow is obtained because of the concentration of mass near the working surface. Furthermore, by the use of the rubber body handle 14, the amount of kick-off normally inherent in dolly blocks is greatly reduced, and this further tends to reduce the danger of injury to the operator's hands often caused by large kick off.

The principal tools used for automotive repair work are a dinging hammer and a dolly block or hand anvil. The working surface of the dolly block is so constructed that different portions thereof will conform to the contour of different portions of the sheet metal structure under repair. The dolly is held against one surface of the sheet metal while hammer blows are delivered to the opposite face of the metal. The hammer is caused to strike the surface of the panel under repair with a glancing blow so as to rebound quickly from the surface of the metal, permitting it to vibrate. The vibration thus set up in the panel aids the damaged portion to return to its normal die-formed shape. With the striking of each blow of the hammer, the dolly is caused to kick away slightly from the surface of the metal, but it returns immediately because of tension in the operator's arm. If the operator holds the bumping surface of the dolly against the surface of the panel with sufficient pressure to overcome the kick off following a hammer blow, stretching of the metal results, thereby increasing the damage and precluding the return thereof to the original form.

A dolly block constructed in accordance with the present invention prevents stretching of the panel as it is worked smooth by hammer blows directed against the panel with the dolly held tightly against the inside of the panel. The cushion effect provided by the rubber body 14 allows the dolly to leave the panel just slightly, and instantly after the blow is struck, thereby minimizing the stretching of the metal. Stretching is thus minimized to such a small factor as compared with the result of using conventional dollies that it is unnecessary to shrink any stretched metal later in the repair operation. Therefore, the efficiency of the repair operation is increased.

Although the personal skill of the operator is important in using dolly block tools, a dolly block constructed in accordance with the principles of the present invention has inherent characteristics which add greatly to the skill of the operator. As soon as the dolly rebounds slightly from the panel under the impact blow of the hammer as described, it instantly returns to the panel with sufficient force to further effect the smoothing of the panel. This return blow strikes the panel while it is still in vibration from the hammer blow, and is the ideal timing for the return blow.

to enable it to further aid the smoothing of the panel. When using conventional dollies, the quick return of the dolly must be entirely performed by the operator's arm. The operator, in attempting to quickly return the dolly of standard design, exerts himself to provide tension in his arms. Even this added tension in the operator's arm is insufficient to imitate the action of my improved dolly, and a great deal of exertion is required which causes quick fatigue. Further, the material used in the cushion grip, namely the rubber body handle 14, is more easily held securely in the operator's hand than the conventional dolly made of steel or cast iron. More accurate placement of the block is thereby obtained. The natural result is more efficient repair work and less fatigue in the fingers from grasping the dolly block.

Dolly blocks are also used in swinging blows to drive or bump out the irregularities in panels. On occasion these blows must of necessity be of great force. The cushion of the rubber body handle 14 thereby protects the operator's hands from injury which sometimes results from this use. It also enables the operator to always use the dolly with its properly shaped working face instead of using a sledge hammer as is sometimes done because of the danger of injury when using standard type dollies. Of course, the dolly with the properly performed working face enables the operator to bump out the panel more smoothly than is possible with a sledge hammer, which neither has the proper shaped working space for this operation, nor can be used with the precision which is essential for producing a relatively smooth shape ready for finishing operation.

Although I have described my invention in its preferred form with a certain degree of particularity, it is understood that the present disclosure of the preferred form has been made only by way of example and that numerous changes in the details of construction and the combination and arrangement of parts may be resorted to without

departing from the spirit and the scope of the invention as hereinafter claimed.

What is claimed is:

- 5 1. A dolly block tool comprising a body of suitable mass and weight to offset the shock of dinging hammer blows, said body comprising a service portion and a grip portion, said service portion comprising a metallic body having a work face, said metallic body having a handle attachment protrusion extending from the metallic body on the side thereof opposite said work face, said grip portion comprising a resilient rubber body having a cavity therein corresponding to the size and shape of said protrusion and having a solid rubber handle portion, said protrusion extending into the cavity of said resilient rubber body, said resilient rubber body being bonded to said service portion and protrusion.
- 10 2. A dolly block tool comprising a body of suitable mass and weight to offset the shock of dinging hammer blows, said body comprising a service portion and grip portion, said service portion comprising a metallic body having a work face, a heel portion, a toe portion, and a handle attachment protrusion, said handle attachment protrusion extending from the metallic body from the side thereof opposite said work face, said grip portion comprising a resilient rubber body having a solid rubber handle portion, said grip portion being bonded to said protrusion of the service portion.
- 15 3. A dolly block tool comprising a body of suitable mass and weight to offset the shock of dinging hammer blows, said body comprising a service portion and grip portion, said service portion comprising a metallic body having a work face, a heel portion, a toe portion, and a handle attachment protrusion, said handle attachment protrusion extending from the metallic body from the side thereof opposite said work face, said grip portion comprising a resilient rubber body having a solid rubber handle portion, said grip portion being bonded to said protrusion of the service portion.
- 20 4. A dolly block tool comprising a body of suitable mass and weight to offset the shock of dinging hammer blows, said body comprising a service portion and grip portion, said service portion comprising a metallic body having a work face, a heel portion, a toe portion, and a handle attachment protrusion, said handle attachment protrusion extending from the metallic body from the side thereof opposite said work face, said grip portion comprising a resilient rubber body having a solid rubber handle portion, said grip portion being bonded to said protrusion of the service portion.
- 25 5. A dolly block tool comprising a body of suitable mass and weight to offset the shock of dinging hammer blows, said body comprising a service portion and grip portion, said service portion comprising a metallic body having a work face, a heel portion, a toe portion, and a handle attachment protrusion, said handle attachment protrusion extending from the metallic body from the side thereof opposite said work face, said grip portion comprising a resilient rubber body having a solid rubber handle portion, said grip portion being bonded to said protrusion of the service portion.
- 30 6. A dolly block tool comprising a body of suitable mass and weight to offset the shock of dinging hammer blows, said body comprising a service portion and grip portion, said service portion comprising a metallic body having a work face, a heel portion, a toe portion, and a handle attachment protrusion, said handle attachment protrusion extending from the metallic body from the side thereof opposite said work face, said grip portion comprising a resilient rubber body having a solid rubber handle portion, said grip portion being bonded to said protrusion of the service portion.
